UNITED STATES PATENT OFFICE.

HAROLD S. COLEGROVE, OF DETROIT, MICHIGAN.

DAVENPORT.

1,319,849.

Specification of Letters Patent.

Patented Oct. 28, 1919.

Application filed October 20, 1917. Serial No. 197,680.

To all whom it may concern:

Be it known that I, HAROLD SIN CLAIRE COLEGROVE, a citizen of the United States, residing at Detroit, in the county of Wayne 5 and State of Michigan, have invented certain new and useful Improvements in Davenports; and I do hereby declare the following to be a full, clear, and exact description of the invention, such as will enable others skilled in the art to which it appertains to 10 make and use the same.

This invention relates to improvements in davenports.

The object of this invention is to provide 15 a device capable of being extended or being converted into a bed or couch.

A still further object of this invention is to improve the construction of a davenport whereby it may be readily extended to provide 20 a head, foot and intermediate sections to constitute a bed.

A still further object of this invention is to provide a convertible davenport having its sections so connected together as to provide 25 a seat and back rest when in folded position.

A still further object of this invention is to provide a davenport of this character, which will be simple, practical and comparatively inexpensive in construction and 30 one that can be manufactured and sold at a low cost.

With these and other objects in view, the invention consists in the novel combination 35 and arrangement of parts hereinafter more fully described and set forth in the claim hereto appended.

In the drawings—

Figure 1 is a perspective view of the 40 davenport in extended position and as made in accordance with this invention.

Fig. 2 is a vertical sectional view partly in elevation of the device when in folded position.

Fig. 3 is a vertical sectional view illustrating the manner in which the foot and intermediate sections are arranged upon one another,

Fig. 4 is a detail sectional view illustrating the manner in which the sections are constructed,

Fig. 5 is a detail sectional view illustrating

the manner in which the foot board is limited in its outward movement,

Fig. 6 is a sectional view illustrating the 55 manner in which the foot board is mounted.

Like numerals of reference designate corresponding parts in all the figures of the drawings.

Referring to the drawings, the numeral 5 60 designates a supporting structure in its entirety and it consists of the rear legs 6 which extend upwardly, front legs 7, arm rests 8, side rails 9. The arm rests 8 are secured by one end to the upper end of each 65 front leg and by their other ends to the rear legs intermediate the ends thereof. It will be apparent that the rear legs extend upwardly beyond the upper ends of the front legs as illustrated in Fig. 1 of the drawings. 70

An inclined back 11 is secured to the rear edges of the rear legs 6 and extends upwardly and is inclined rearwardly therefrom due to the position of the rear legs 6. 75

A pair of angle brackets 12 are provided each being secured by its vertical flange to one of the opposing faces of the front legs intermediate the ends thereof and the securing 80 of the brackets by the vertical flange to the legs positions their horizontal flanges inwardly in the direction of each other. The side rails 9 which are secured to the front and rear legs are each provided on their inner sides adjacent the forward edge 85 with a roller 10, which roller extends horizontally therefrom, the purpose of which will be hereinafter more fully described.

A head section 13 including a substantially rectangular frame is pivotally secured as at 90 14' to the opposing faces of the rear legs 6. The head section is adapted to be swung downwardly on its pivot at right angles to the back 11 so as to provide the head section of the bed and the forward edge of 95 the frame rests upon the brackets 12. When it is desired to use the device as a chair or couch, the bed section is swung upwardly on its pivot into engagement with the front face of the back 11, thus hiding the bed 100 portion of the head section 13.

It is to be understood that the length of the head section 13 is less than the space between the side rails 9 so as to permit the

head section to be moved into different positions.

An intermediate section 14 includes a substantially rectangular frame, the side rails 5 of which are provided exteriorly with longitudinally extending grooves 15 in which the rollers 10 are adapted to operate to permit the intermediate section to be moved into and between the side rails when the head 10 section is swung upwardly against the back 11. A foot section 16 is hingedly secured as at 17 to the forward edge of the intermediate section 14 and the foot section frame is adapted to be swung rearwardly upon the 15 upper side of the intermediate section 14 prior to the intermediate section being pushed in between the side rails 9 of the supporting structure 5.

A plurality of legs 18 are pivotally secured as at 19 to the opposite ends of the end rails of the rectangular frame of the foot section and these legs are adapted to be swung downwardly in the position illustrated in Fig. 1 to support the device in an 20 extended position. It is to be understood that the legs are first folded upwardly in the position illustrated in Fig. 2, the head section swung up against the back 11, and the intermediate section shoved in between 25 the side rails and the foot sections swung rearwardly against the upper side of the intermediate section 14 and the device may be used as a chair, couch or the like.

The head section 13 has secured therein a 30 suitable spring 19, and on the rear side of the spring is secured a suitable felt packing 20 which constitutes a mattress, it being covered by suitable ticking 21. Secured on the forward face of the spring is the upper 35 holstering 22 which is held extended by a suitable packing 23, thus it can be seen that when the section 13 is up against the back 11, the cushion or upholstering 22 will constitute a back rest for persons seated upon 40 the davenport. The intermediate section 14 has secured in its frame a suitable spring 24 which has secured on its under side a suitable cover 25 constituting an inclosure for the spring. A mattress 26 is secured upon 45 the upper side of the spring 24 and is covered by a suitable ticking 27 and this mattress is adapted to be flush with the mattress 20 of the head section 13 when in an extended position as illustrated in Fig. 1.

50 The frame 16 of the foot section has secured therein a spring 28 which has secured to its upper side a mattress 29 which is covered by a suitable ticking 30. This mattress is adapted to be flush with the mattress 55 of the intermediate and head sections when the device is in its extended position.

Secured to the under side of the spring 28 of the foot section is a suitable packing 31 which is covered by suitable upholstering 32 60 and this constitutes a seat for the davenport

when the device is in a folded position as illustrated in Figs. 2 and 3 of the drawings.

An inverted U-shaped foot board 33 has secured to the terminals of its arms the collars 34, which collars have formed integrally therewith and concentrically related thereto, apertured lugs 35. The lugs 35 are pivotally secured by suitable fastening means, such as bolts or the like, designated 37 to the side walls of the recesses 36 formed in the 70 front rail of the foot section 16. The recesses 36 are formed in the upper edge of the front rail adjacent each end thereof and this permits the foot board to be moved into a vertical position with relation to the section 16 and swung downward to rest upon and in the frame 16 when the sections are folded to closed position. It is understood that frictional contact of the lugs with the side walls of the recesses holds the foot 80 board in either of its positions.

In use, when it is desired to extend the chair, the operator grasps the seat and to throw the same outwardly it is swung on its hinge in a horizontal position and the legs 90 18 are then forced downwardly and the intermediate section pulled outwardly until it rests upon the angle brackets on the forward legs 7. The head section is then forced downwardly until it rests upon the angle 95 brackets of the legs 6 and 7 and it is then only necessary to make the bed in the same manner as beds now in general use by covering the mattress of each of the sections with a suitable covering.

When it is desired to use the same as a couch or chair, it is only necessary to fold the head section upwardly against the back 11. The intermediate section is then forced inwardly through the medium of the rollers 10 and positioned between the side rails 9. The legs 18 are then folded upwardly and the foot rest downwardly against the mattress and the foot sections swung against the intermediate section and the device is folded 105 and ready for use as a chair or couch, it being understood that by virtue of the head section being pivoted it may be readily swung up against the back 11.

What is claimed is:

A davenport comprising a supporting structure, front and rear brackets carried by the said structure, a head section pivoted to said structure for movement into raised or lowered position and adapted when in lowered position to be supported by said front bracket and the pivot, a back carried by said structure and arranged in an upwardly and rearwardly inclined position and adapted to support said head section 120 when the latter is in raised position, an intermediate section slidably mounted on said brackets and having elongated slots in the sides thereof, said intermediate section 125 being supported when in retracted position 130

by said brackets and the rear end of said intermediate section being supported when in extended position by said front brackets, rollers journaled upon said structure and 5 located in said slots, a foot section hinged to the front end of said intermediate section, and legs pivoted to the sides of said foot section adjacent the front and rear ends thereof to support said section and the front end of the intermediate section when 10 said sections are extended.

In testimony whereof I affix my signature in presence of two witnesses.

HAROLD S. COLEGROVE.
